[57] CLAIM

The ornamental design for a wet location wiring device cover, substantially as shown and described.

DESCRIPTION

FIG. 1 is a perspective view of a wet location wiring device cover showing my new design, in the closed position;

FIG. 2 is a left end elevational view thereof;

FIG. 3 is a rear elevational view thereof;

FIG. 4 is a bottom plan view thereof;

FIG. 5 is a perspective view thereof, in the open position with the receptacle inserts and screw shown in broken lines for illustrative purposes only;

FIG. 6 is a bottom plan view of a second embodiment of the design of FIG. 1, the only difference being the configuration of the receptacle opening and the number of screw holes;

FIG. 7 is a perspective view of FIG. 6, in the open position with the receptacle insert and screws shown in broken lines for illustrative purposes only.
